Primary Examiner — Nathan M Johnston(74) *Attorney, Agent, or Firm* — Malloy and Malloy, P.L.;
Jennie Sue Malloy(57) **CLAIM**

The ornamental design for a self-righting tip cap, as shown and described.

DESCRIPTION

FIG. 1 is a front perspective view illustrating my design for a self-righting tip cap;

FIG. 2 is a front elevation view, with the rear view, right side view and left side view being mirror images thereof;

FIG. 3 is a top plan view thereof;

FIG. 4 is a bottom plan view thereof; and,

FIG. 5 is a cross-sectional view thereof taken along the lines 5-5 shown in FIG. 3.
